[57] CLAIM

The ornamental design for a charger for a wireless telephone, as shown and described.

DESCRIPTION

FIG. 1 is a perspective view of a first embodiment of a charger for a wireless telephone showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a perspective view of a second embodiment of a charger for a wireless telephone showing my new design;

FIG. 8 is a top plan view of the embodiment of FIG. 7;

FIG. 9 is a left side elevational view of the embodiment of FIG. 7;

FIG. 10 is a front elevational view of the embodiment of FIG. 7;

FIG. 11 is a bottom plan view of the embodiment of FIG. 7;

FIG. 12 is a right side elevational view of the embodiment of FIG. 7; and,

FIG. 13 is a rear elevational view of the embodiment of FIG. 7.

Body, and antenna portions shown in broken lines are for illustrative purposes only and form no part of claimed design. The portion of the base hidden behind the broken line antenna attachment is not a part of the claimed design.
